GUN PLATFORM

Mieth Maeser, Beverly, Mass., assignor to United
Shoe Machinery Corporation, Flemington,
N. J., a corporation of New Jersey

Application November 19, 1943, Serial No. 510,989

13 Claims. (Cl. 89—40)

1

This invention relates to a platform upon which such objects as guns may be supported, and is particularly concerned with a wheeled platform which may be set up in a fixed position for the firing of the gun, or may be mounted upon its wheels for transfer from one point to another.

The invention has as an object the provision of a platform of the character indicated above, which, when demounted, will furnish a stable support for the gun during discharge, yet which is so small and light that it may be transformed quickly into a compact wheeled carriage by relatively few men, the arrangement of the parts being of such a character that handling is facilitated. With this end in view, my improved platform has a central support for the gun, to the opposite sides of which support bars are secured, these diverging rearwardly from an apex to points beyond the support, they being connected by a crossbar at the rear of said support. Such a structure alone furnishes well-placed areas to resist overthrow. It is, moreover, a light skeleton-frame, the side-bars being in the form of channel-bars and the crossbar an angle-bar. The frame is further stayed by an axle-bar connected between the side-bars at the rear of the crossbar and adapted to receive wheels. The gun-support is preferably a ring resting upon the upper flanges of the channel-bars and upon the upper arm of the angle-bar, to which it is secured. The ring may be strengthened by a chord extending between its sides and by depending flanges upon the ring and chord. Openings through which the gun-standard is bolted to the ring are strengthened by plates secured at their opposite sides, there being bolt-retaining means between the plates. All the connections between the frame-members are furnished by welds.

To increase the stability of the platform when in its fixed position, braces are preferably pivoted to the side-bars at opposite sides of the central support. Each brace may be held in its active relation, extending from its side-bar, by a single pivoted stay engaging the side-bar and brace and being secured to said brace both when this is active and inactive. Adequate contact-area with the ground or other supporting surface is provided by feet in the form of plates secured to the frame and its braces, a portion of which feet are at points distributed at substantially uniform angles about the center of the support and at substantially equal distances from said center.

When the locations of the platform and gun are to be changed, rear wheels are applied to the ends of the axle-bar and a towing truck to the

2

apex of the side-bars. To facilitate this operation and to guard against the entrance of dirt to the wheel-bearings, each rear wheel and its axle constitutes a unit, the axle being separably attached to the axle-bar. The assembling of these wheel-units with the frame is made easy and their security insured by bores in the axle-bar decreasing in diameter inwardly, and corresponding portions of the axles fitting the bores, together with means, in the form of a tapered key, for forcing the axle into place and retaining it. To attach the forward truck to the platform, a vertical sleeve is preferably secured to the apex of the side-bars, and the truck has plates extending above and below the ends of the sleeve, in which plates are openings for registration with the passage through the sleeve. In the openings and passage a pintle is received and arranged similarly to the rear axles and their receiving openings in the axle-bar. To guard against rolling out of position, the truck may be locked in longitudinal alinement with the platform.

In the accompanying drawings illustrating a particular form of the invention,

25 Fig. 1 shows my improved platform in side elevation, mounted upon its wheels and carrying a gun;

Fig. 2 is a top plan view of the platform, with parts broken away and the gun omitted, it resting upon the ground with its wheels removed in firing position;

Fig. 3, a front elevation of the parts appearing in Fig. 2;

Fig. 4, a top plan view of the forward extremity of the frame with the attached truck, portions being in section;

Fig. 5, a vertical section through one end of the axle-bar, together with the attached axle and the hub of the surrounding wheel;

40 Fig. 6, an enlarged vertical sectional detail through the gun-supporting ring and the cross-bar of the frame on the line VI—VI of Fig. 2;

Fig. 7, a like view of the connection between the ring and the side-bar of the frame on the line VII—VII of Fig. 2;

Fig. 8, a similar view through the ring and its chord on the line VIII—VIII of Fig. 2;

Fig. 9, an enlarged vertical sectional detail of the pivotal connection between one of the braces and the frame, taken on the line IX—IX of Fig. 2;

Fig. 10, a similar view on the line X—X of Fig. 4, showing the connection between the frame and the forward truck; and

Fig. 11, an enlarged broken vertical section through the tool-box on the line XI—XI of Fig. 2.

Throughout these figures, welded joints are represented by dotted hachuring.

The platform has a body-portion in the form of a skeleton-frame P, preferably consisting chiefly of structural steel-shapes, the opposite sides of which frame are furnished by channel-bars 10, 10 having their webs vertical and turned outwardly. These bars diverge to the rear from a vertical sleeve 12 to the opposite sides of which they are welded. The structure here is stiffened by trapeziform plates 13, 13 welded to the edges of the upper and lower flanges of the bars 10 (Figs. 2 and 10). These bars are joined at points spaced from their opposite or rear extremities by a stay provided by a cross angle-bar 14, having a horizontal arm welded flush to the upper flange of each channel-bar and a vertical arm extending between the flanges and welded to the web of each channel-bar (Fig. 11). Beyond the crossbar, the upper flange of each side-bar is inclined downwardly toward the end. Through openings in the webs of the side-bars, between the crossbar 14 and their ends, extends a tubular axle-bar 16 welded to the side-bars and furnishing an additional stay. The outer ends of the axle-bar are reinforced by opposite ribs 18, 18, welded to them and to the webs of the side-bars. The use of this axle-bar for mounting the rear wheels, which transform the platform into a carriage, will later be explained. Resting upon the upper flanges of the side-bars 10, 10 and upon the crossbar 14, and preferably extending to their outer edges, is a ring 20 welded to the supporting bars. The ring has integral with it a chord 22 lying between the resting points upon the side-bars. To the inner circumference of the ring is welded a depending flange 24, while opposite flanges 26, 26 are welded to the edges of the chord and at their ends to the ring-flange and to the side-bars (Fig. 8). The ring provides the support for the circular base 28 of the standard 29 of a gun G, which is to be mounted. In this base are a series of openings 30 through which bolts 32 pass into registering openings 34 in the ring 20. At each side of each opening, save that at the rear, the ring is strengthened by opposite vertical transverse plates 36, 38. Each of the plates 36, as viewed in side elevation, is triangular, the upper and vertical edges of the plates being welded to the ring 20 and flange 24, respectively (Fig. 8). Each of the other plates 38, at one end, is similarly welded to the ring 20 and flange 24 and extends outwardly to one of the side-bars 10, where it is welded to the web and to the upper flange of the adjacent side-bar (Fig. 7). Between the plates 36 and 38, against the under side of the ring, a horizontal plate 40 is welded, this having a depression 42 to receive the head of the bolt 32 and prevent it from turning when the nut 33 is being set down upon the base 28. At the rear opening 34 the plates 36, 36 are welded to both arms of the crossbar 14 (Fig. 6). Between this crossbar and the axle-bar 16 a sheet-metal tool-box 46 is supported (Fig. 11), the top conforming to the inclination of the side-bars and being welded at the ends to these side-bars (Fig. 2) and at the forward wall to the crossbar (Fig. 11). The box has a cover formed in sections 48, 48, retained at their inner edges 49 beneath the upper arm of the crossbar and at the outer or rear edges by a series of hooked spring-catches 50. Near the center, the box is stiffened by a sectional strip 51 welded about it and at its upper forward extremity to the crossbar 14, the upper portion furnishing a

support for the inner ends of the cover-sections.

Since the platform as above described is intended to furnish a stable mounting for the gun during its firing, it is provided with the following means for engagement with the ground or other surface upon which it is to be supported. Near the apex of the platform, just at the rear of the filler-plates 13, vertical plates 52, 52 are spaced from each other (Fig. 10), they 10 resting upon the lower flanges of the side-bars 10, 10. They are welded to these flanges, and at their ends to the webs of the bars. To them, below the side-bars, a plate 54 is welded, this furnishing a foot. To the side-bars, near the 15 opposite sides of the ring 20, two additional feet 56, 56 are secured, a plurality of interposed spacers 57 being welded to them and to the lower flanges of the side-bars. At the rear extremities of the side-bars feet 58, 58 are similarly 20 attached. Through the upper and lower flanges of the bars and through the feet 58 downwardly and forwardly inclined openings 60 are formed, to permit spikes or spades to be driven through them into the ground, these preventing displacement of the platform when in firing position. 25 For the same purpose, the plate 54 has an opening 61. The feet 56 give direct vertical support to the mounted gun, while the feet 54 and 58 provide well-spaced areas of engagement fore and aft 30 to retain it against overturning.

To give adequate lateral resistance to overthrow without adding appreciably to the bulk of the platform when being moved, there is at each side a brace furnished by a pivoted arm 62. Each 35 arm may be in the form of a channel-bar with its upper flange inclined downwardly and outwardly from the pivot. To the outer sides of the upper and lower flanges, hinge-plates 64, 64 are welded, the flanges between the hinge-plates being 40 stiffened by a vertical plate 66 welded to them. The plates 64, 64 of each arm respectively lie above and below the hinge-plates 68, 68, welded to the outer side of the web of one of the side-bars 10 opposite the rear portion of the ring 20. 45 To allow each arm 62 to turn upon its pivot without play, and so resist effectively the shock of gun-discharge and to permit any wear to be taken up readily, the pivotal openings 70, 70 in the plates 64 (Fig. 9) are conical, they converging inwardly, while the conical registering openings 72, 72 in the plates 68 are oppositely inclined. A bolt 74 passing through each pair of openings 70, 72 has a conical head 76 seated in the former, and is surrounded by a divided conical washer 78 within the latter. Upon each bolt 50 are a nut and lock-nut 80, which when tightened draw the hinge- and bar-plates together without the possibility of lateral movement or side-play, and permit this condition to be maintained as 55 wear is introduced. At the end of each brace-arm opposite its pivot, a foot-plate 82 is carried at the underside, it being spaced from the lower flange of the channel by a plurality of bars 84 welded to both. The two feet 82 lie in the plane 60 of the feet 54, 56 and 58. A downwardly and inwardly inclined opening 86, through the flanges of the brace and through each foot, allows the driving through it of a spike or spade, as for the feet 54 and 58. Each brace has two normal positions, either folded against the corresponding side-bar 10 when the platform is in transit, or extended when said platform is fixed for the operation of the mounted gun. In the latter relation, the brace may be secured by a stay-arm 88. Each 65 stay-arm is pivoted by a pin 90 between projec- 70

tions 92, 92 from the web of the corresponding side-bar, and has at its outer extremity a vertical opening 94. With the brace folded forward in its inactive position against the side-bar, the opening may be brought into registration with openings in spaced projections 98, 98 from the web of said brace. Here it may be secured by a pin 100 passing through the openings and attached to the brace by a chain 102. The folded brace is secured by a pin 104 similarly attached and received in vertical openings in spaced blocks 106, 106 welded to the inner sides of the upper and lower flanges of the brace and in a projection 108 from the side-bar. With each brace in its active position at right angles to the side-bar, the pin 104 is received in the stay-opening 94 and in the brace-openings in the blocks 106. The pin 100 may be supported idly in the projections 98.

To facilitate the transportation of the platform and mounted gun from place to place, it is provided with a pair of rear wheels 120, 120 and a forward wheel 122, all of which may readily be applied and removed. Each of the wheels 120 is received upon one end of the axle-bar 16. The manner of mounting the wheels 120 is the same, so only one will be described. In the axle-bar is a stepped axial bore of two diameters, the inner portion 124 being less than the outer 126 (Fig. 5). Opening into the bore 126 through the top and bottom of the bar are vertically aligned slots 128, 128. The bore 124, 126 receives the shank of an axle 130. Upon this axle the wheel 120 is rotatable between an inner flange 134 integral with the axle and an outer washer 136 retained in place by a cotter-pin 138 passing through the washer and axle. The shank of the axle is stepped, it being shown as having a short tapered end 140 followed by a cylindrical portion 142 fitting the portion 124 of the bore. From this, a tapered portion 144 leads to a cylindrical portion 146 of maximum diameter extending to the flange 134 and fitting the bore 126. Through the shank-portion 146 is a slot 148, having its inner wall 150 inclined downwardly and outwardly and which may be brought into registration with the bar-slots 128. With the axle-shank in the axle-bar-bore and the slot 148 alined with the slots 128, a key 152 may be inserted from above and driven into place. The key is tapered or wedge-shaped, with its inner edge 154 inclined complementally to the wall 150 of the slot 148 and contacting therewith. Between the inclined edge 154 of the key and the adjacent ends of the slots 128 and between the opposite outer edge of the key and the opposed wall of the shank are clearance spaces. The effect of the insertion of the key, with the resulting pressure of the key-edge 154 against the shank-wall 150, is to force the flange 134 firmly against the end of the axle-bar, and retain the axle and shank securely in place. During application and removal, the axle and wheel remain a unit without occasion for separation. When the axle-shank is applied to the bore in the axle-bar, its tapered end 140 leads the way for the portion 142 into the bore 124. This alines the axis of the shank with that of the bore, so when the shank-portion 146 reaches the bore 126 it is guided in. The effort required in applying the axle and its wheel to the bar is thus minimized. In disassembling, the key is knocked out, leaving the axle and wheel free for removal. The key may be kept with the platform by a chain 156, which secures them together.

The forward wheel 122 is rotatable upon a pivoted truck or limber, designated as a whole by F.

This truck is in the form of a yoke, the spaced arms 164, 164 of which are furnished by shallow channel-bars having their upper and lower flanges converging forwardly. At the rear they are joined by being welded to upper and lower horizontal plates 166 and 168, respectively (Fig. 10), so spaced that they extend just above and below the ends of the vertical sleeve 12 at the apex of the platform. The horizontal plates are stayed by a transverse vertical plate 169 welded to them. In the plates 166 and 168 are openings 170 and 172, respectively, axially aligned with the passage 174 through the sleeve. To the underside of the upper plate, about its opening 170, a ring 176 is welded to give a limited surface bearing upon the end of the sleeve. The truck is separably pivoted to the platform by a pintle 178 passing through the openings 170, 174 and 172. The openings and pintle have portions of different diameters, similar in relation and functions to those of the shank of the axle 130 and its receiving bore in the axle-bar. That is, the pintle has a leader 180, the end of which is tapered and above this is a larger portion 182 fitting the plate-opening 172 and the lower reduced portion 186 of the sleeve-passage 174. Next is a portion 186 between which and the passage is a clearance-space serving as a reservoir for a lubricant, followed by a portion 188 fitting the upper portion of the passage of maximum diameter. Finally, the head or terminal fits within the plate-opening 170. A hand-hold 189 projecting from the head facilitates the manipulation of the pintle. Contact between a shoulder 190 at the juncture of the bore-portion 184 and the main bore 174 and a shoulder 192 between the portions 186 and 188 of the pintle, limits the downward movement of said pintle. Upward displacement and the entrance of dust and the like are prevented by a cover-plate 194, pivoted at 196 upon the upper plate 166 and held normally closed by a thumb-screw 198 threaded into the plate. The wheel 122 of the truck turns about an axle-rod 200. This passes through horizontally aligned openings 202, 202 in the forward extremities of the yoke-arms 164. Outside the yoke-arms, openings in the ends of a forked handle 206 receive the axle-rod, so said handle may be swung vertically upon the rod to conform to the direction of pull in towing. A head 208 upon one end of the rod and a washer 210 secured by a cotter-pin 212 upon the other end engage the outer sides of the branches of the handle. A crossbar 214 passing horizontally through the outer end of the handle furnishes a hand-hold, and a stay 216 between the branches strengthens it. When the platform, on its wheels, is left upon an irregular surface or incline, its truck F may tend to so turn that the platform will roll out of position. To prevent this, the truck may be locked in longitudinal alinement with the platform by such means as one of the spikes which are used to secure the feet. This spike is passed through openings 220, 220 in rearward extensions 222, 222 of the plates 166 and 168 and openings 224, 224 in the frame-plates 13, 13, registration of the openings 222 and 224 being established when the truck is in the desired position.

Assuming that initially the platform P is set up for gun-discharge, the forward truck F and the rear wheels 120, with their axles 130, have been removed. The bracing arms 62, 62 are extended at right angles to the side bars 19, 19, they being held in the correct relation by the stay-arms 88, 88, which, respectively, join each arm 62 to the

corresponding side-bar. This is as appears at the front of Fig. 2. All the foot-plates 54, 56, 58 and 82 rest upon the ground to carry and brace the platform, the feet 56 beneath the gun-supporting ring 20 being effective to carry directly the weight of the gun and its standard. The remaining feet are distributed about the center of the ring at points which lie approximately at the ends of the radii of a pentagon. Consequently, they are so placed as to angular relation and distance from the center that they offer equal and adequate resistance to the displacement of the platform upon the discharge of the gun in any direction. Because of the character of the pivots for the bracing arms furnished by the conical engaging surfaces at 70, 76 and 72, 78, a comparatively rigid connection may be at all times maintained, in spite of the turning of the arms and the shocks to which the gun-discharge subjects them.

When the platform and gun are to be moved to another location, the stay-arms are disengaged from the bracing arms and both pairs of arms folded against the side-bars. This, as shown at the rear of Fig. 2, gives the platform a small average lateral extension. Because of its skeleton-frame made up of light structural shapes, the platform adds relatively little to the weight of the gun and may easily be lifted from the ground by a small group of men. The shanks of the axles 139, with the wheels 120 upon them, are inserted in the bores in the ends of the axle-bar 16 with the slots of the shanks and bar in registration, the stepped arrangement of the shanks and bore-portions making this easy. Then the keys 152 are driven into place to secure the wheel-units upon the frame. Because of the constant association of the wheels and axles, dirt is at all times excluded from the bearings. The plates 170, 172 of the forward truck F, carrying the wheel 122 upon its axle-rod 200, are placed upon opposite ends of the frame-sleeve 12, with the stepped plate- and sleeve-openings alined, and are pivotally connected by the stepped pintle 178. The platform is now ready for towing by the handle 206.

It is to be noted that at all times, whether in motion or arranged for firing the mounted gun, the platform-frame is a unitary structure having all its elements welded to one another and with nothing to work loose. The portion bearing the direct weight of the gun offers great resistance to bending. The ring 20 receives support about a considerable extent of its circumference from the side-bars 10, 10 and the crossbar 14. It is stiffened by its flange 24 and braced transversely by its chord 22 with the flanges 26, said flanges being joined to the side-bars. It is further strengthened by the radially arranged plates 35, 38, with their connection to the side-bars. As to the remainder of the frame, the side-bars are securely joined by the central portion, as just pointed out, and at the contracted front or apex by the sleeve 12, the horizontal plates 13 and the vertical plates 52, the latter also carrying the foot-plate 54. At the diverging rear of the side-bars, the crossbar 14 ties them in such a manner as to resist bending, both horizontally and vertically, to which is added the effect of the axle-bar 16.

Having described my invention, what I claim as new and desire to secure by Letters Patent of the United States is:

1. A gun-platform having a central support on which the gun may be mounted, bars secured to the support at opposite sides and meeting at an

apex, said bars diverging rearwardly to points beyond the support, a crossbar secured to the side-bars and to the rear of the support, and an axle-bar connecting the side-bars at the rear of the crossbar and adapted to receive wheels.

2. A gun-platform including channel-bars diverging rearwardly and with their webs at the outer sides, an angle-bar extending between the flanges of the channel-bars at points toward their rear extremities and having an upper horizontal arm lying in the plane of the upper flanges of the channel-bars, welds connecting the angle-bar to the webs and upper flanges of the channel-bars, a gun-supporting ring resting upon the upper flanges of the channel-bars and the upper arm of the angle-bar, and welds connecting the ring to the channel-bars and angle-bar.

3. A gun-platform including channel-bars diverging rearwardly and with their webs at the outer sides, an angle-bar extending between the flanges of the channel-bars at points toward their rear extremities and having an upper horizontal arm lying in the plane of the upper flanges of the channel-bars, and a gun-supporting ring resting upon the upper flanges of the channel-bars and the upper arm of the angle-bar and secured thereto, the ring having a chord extending between points adjacent to the points of support of said ring upon the channel-bars, there being depending flanges from the inner circumference of the ring and the edges of the chord the chord-flanges being secured to the channel-bars.

4. A gun-platform including channel-bars diverging rearwardly and with their webs at the outer sides, an angle-bar extending between the flanges of the channel-bars at points toward their rear extremities and having an upper horizontal arm lying in the plane of the upper flanges of the channel-bars, welds connecting the angle-bar and channel-bars, a gun-supporting ring resting upon the upper flanges of the channel-bars and the upper arm of the angle-bar, the ring having a chord extending between points adjacent to the points of support of said ring upon the channel-bars, there being depending flanges from the inner circumference of the ring and the edges of the chord, welds connecting the ring to the upper surfaces of the channel-bars and angle-bar, and welds connecting flanges of the chord to the flange of the ring and to the channel-bars.

5. A gun-platform including channel-bars diverging rearwardly and with their webs at the outer sides, an angle-bar extending between the flanges of the channel-bars at points toward their rear extremities and having an upper horizontal arm lying in the plane of the upper flanges of the channel-bars, a gun-supporting ring resting upon the upper flanges of the channel-bars and the upper arm of the angle-bar and being provided with bolt-receiving openings and with a depending flange, and a strengthening plate secured to the ring and to the flange at each side of each opening, one of said plates being also secured to the adjacent channel-bar.

6. A gun-platform including channel-bars diverging rearwardly and with their webs at the outer sides, an angle-bar extending between the flanges of the channel-bars at points toward their rear extremities and having an upper horizontal arm lying in the plane of the upper flanges of the channel-bars, a gun-supporting ring resting upon the upper flanges of the channel-bars and the upper arm of the angle-bar and being provided with bolt-receiving openings and with a depending flange, a strengthening plate secured

to the ring and to the flange at each side of each opening, one of said plates being also secured to the adjacent channel-bar, and a bolt-retaining plate secured to the ring and to the strengthening plates.

7. A gun-platform having a support upon which a gun may be mounted, bars secured to the support at opposite sides, said bars diverging rearwardly to points beyond the support, braces pivoted to the side-bars at opposite sides of the support and movable between active and inactive positions, a stay for each brace pivoted to the side-bar for engagement of the end of said stay with the brace, and means for securing the end of each stay to its brace in both its active and inactive relations.

8. A gun-platform having a central support on which the gun may be mounted, bars secured to the support at opposite sides and meeting at an apex, said bars diverging rearwardly to points beyond the support, a crossbar connecting the side-bars at the rear of the support, platform-supporting feet carried beneath the side-bars adjacent to the apex and to the rear extremities, braces pivoted to the side-bars at opposite sides of the central support to extend outwardly therefrom, and platform-retaining feet carried beneath the braces, all the feet being at substantially equal distances from the center of the support and spaced by substantially equal angles about said center when the braces are extended.

9. A wheeled gun-platform including a gun-support, diverging bars secured at opposite sides of the support, an axle-bar connecting the diverging ends of the side-bars, there being at each end of the axle-bar a bore having portions of different diameters decreasing inwardly, an axle provided with portions fitting the different bores, securing means arranged to force the axle into place in the bores, and a wheel rotatable on each axle.

10. A wheeled gun-platform including a gun-support, bars secured at opposite sides of the support, an axle-bar connecting the ends of the side-bars, there being at each end of the axle-bar a bore having portions of different diameters decreasing inwardly, axles provided with portions fitting the different bores, there being cooperating slots through opposite sides of each end of the axle-bar and through the cooperating axle, said slots having at one end inclined walls, and a tapered key passing through the slots and engaging the inclined walls.

11. A wheeled gun-platform including a central support for the gun, bars secured to the support at opposite sides, a vertical sleeve to which the bars converge and to which they are secured, a forward wheeled truck having plates

extending above and below the ends of the sleeve and provided with openings for registration with the passage through the sleeve, a pintle passing through the plate-openings and through the passage, an axle-bar secured to the diverging rear extremities of the side-bars, and wheels rotatable upon the opposite ends of the axle-bar.

12. A wheeled gun-platform including a central support for the gun, bars secured to the support at opposite sides, a vertical sleeve to which the bars converge and to which they are secured, a forward wheeled truck having plates extending above and below the ends of the sleeve and provided with openings for registration with the passage through the sleeve, the passage and openings through said sleeve and plates having portions of different diameters decreasing downwardly, a pintle provided with portions fitting the sleeve portions, an axle-bar secured to the diverging rear extremities of the side-bars, and wheels rotatable upon the opposite ends of the axle-bar.

13. A wheeled gun-platform including a central support for the gun, bars secured to the support at opposite sides, a vertical sleeve to which the bars converge and to which they are secured, a forward wheeled truck having plates extending above and below the ends of the sleeve and provided with openings for registration with the passage through the sleeve, a pintle passing through the plate-openings and through the passage, an axle-bar secured to the diverging rear extremities of the side-bars, wheels rotatable upon the opposite ends of the axle-bar, and means for locking the truck in longitudinal alignment with the platform.

MIETH MAESER.
